UNITED STATES PATENT OFFICE

BRUNO D. LEVI, OF NEW YORK, N. Y.

PENCIL AND SHARPENER

Application filed February 12, 1929. Serial No. 339,303.

This invention relates to new and useful improvements in pencils and has for its object to provide a unique combination of a two in one device, that is of a pencil and a sharpener, which will have a great scope of usefulness as the sharpening elements, which may be employed in conjunction with the actuating means therefor, may be used for a similar purpose in case of cosmetic sticks, 10 crayons and even toothpicks.

The specific construction herein provided for will at all times prevent the clogging up of a pencil, as is now the case with the kinds commonly used. At the same time with the 15 self sharpening features employed, a pencil of this sort will always be ready for use and prove a great time-saving device.

It deserves in this connection to be pointed out as a distinct advantage, that the arrangement herein described will prevent any rattling or shaking of the lead when the device 20 is used for the purpose of writing.

The construction is further to the effect that parts of the device may be exchanged and 25 renewed in case of any damage and breakage.

By a slight modification of the construction space may be provided and arrangement made to receive reserve sticks of lead; in like 30 manner the usual rubber-eraser may be attached to the lower end of the pencil in any convenient manner.

It has been an object to make this device 35 strong, durable and easy to operate, and as the construction is comparatively simple the cost of manufacturing should be relatively low.

With the above and other objects in view, 40 this invention consists of the novel features of construction, combination and arrangements of parts, hereinafter fully described, claimed and illustrated in the accompanying drawings forming parts of this specification, and in which similar characters of reference 45 indicate corresponding parts in all views, and in which:

Figure 1 is a transverse sectional view of 50 my device; Fig. 2 is a sectional view taken on line 2—2 of Fig. 1; Fig. 3 is a central sectional view of the top portion; Fig. 4 is a similar

view of my device slightly modified; Fig. 5 is a detail view of the clutch member; Fig. 6 is a detail view in section of the clutch member illustrating especially the plunger; Fig. 7 is a detail view of another embodiment of my 55 device; and Fig. 8 shows a slight modification of the latter in section, while Fig. 9 shows an eraser attachment.

Referring more particularly to the drawings, 10 indicates my device comprising an outer substantially cylindrical member or barrel 11, to which is attached, in an integral manner if desired, an inner tube 12 adapted to receive a lead-member 13. The said tube 12 is of a preferably polygonal, in this present 60 instance, hexagonal form, in cross-section, as will be clearly seen in Fig. 2. In fastening the tube 12 to the tubular member 11, it will be noticed that the said attachment only takes 65 place with reference to the lower sections of the said two members, as indicated, at 14, leaving a cylindrical space 15 between the upper portions of the said two members 11 and 12.

The lower end portion of the said device 70 is closed by a cap-member 16, which may be screwed onto or fastened to the members 11 and 12, or any one of them, as desired, and have provision made for carrying a rubber 75 eraser.

A clutch-member 17, of a cross-sectional shape substantially as the inner tube member 12, is mounted upon the latter and adapted to slide up and down upon the said tube-member 12 when engaged or acted upon by a top member 18 by means of a screw-threaded engagement. The said member 18 has a reduced cylindrical bottom portion 19 fitted to be mounted within the member 11 in such a manner that the shoulder-portion 20 of the 80 said member 18 ordinarily will rest upon the upper edge of the cylindrical member 11, as indicated at 21.

The said member 18 has its cylindrical bottom portion 19 provided with threads upon its inner side, as at 22 for the purpose of securing a meshing engagement with the clutch member 17; and as the sections effecting the said engagement are very finely threaded a slow motion may be obtained, 95 100

suitable to the process of sharpening the lead of a pencil, this is a feature of special importance when the means employed to that end are abrasive as, for instance, emery, corundum, or a file member.

8 The top member 18 has a special constructed point section 23, which may be rigidly or detachably secured to the said member 18, according to whether provision is made 10 for replacement of the said point section. The member 18 has disposed at its center a tapered bore 24, which is formed according to the means employed for sharpening the lead; thus the said sharpening process may 15 be effected by forming the bore with screw-threads, as shown in Fig. 3, or grooves, or by arranging a special grinding member within the said bore, the latter member may consist of any hard and suitable material, 20 as corundum, carborundum, emery, etc. The said sharpening may also be accomplished by forming the said conical point section with an inner bore made as a file. It is evident that by turning the top member 18 with its 25 point section 23 the simultaneous cooperation between the section 19 and the clutch-member 17 with its plunger will, as shown, force the lead-stick 13 through the tapered bore 24 and thereby accomplish the sharpening of the former. It will be observed that 30 ordinarily the tube member 12 abuts with its upper end against the lower part of the point section 23 as shown at 27.

The clutch member 17 has disposed a 35 plunger 25 adapted to project into the tube 12 through the longitudinal split 26 formed in the latter, the said split extending almost to the top edge of the said tube. In operating the said device by turning the top member 18 40 the lower section 19 thereof will engage the clutch 17 and urge the latter upward during which operation a pressure in an upward direction simultaneously is exerted upon the lower end of the lead 13 by the plunger 25 45 thereby feeding the said lead to the grinding parts of the point section 23, which actually perform the work of sharpening.

While the arrangements herein described have contemplated the use of a lead-stick of 50 a polygonal shape, a round lead-stick may well be used by employing a special hood member as shown in Fig. 7 and consisting of a somewhat cylindrical barrel formed with a slight outward flaring 32 in an upward 55 direction in order to make the said barrel especially suitable for exerting a tight grip upon a round lead stick and thereby preventing the latter from turning when being sharpened during the grinding operation. As a 60 further means serving the latter purpose the said barrel may be provided with an inner surface having disposed longitudinal grooves 33, as shown in Fig. 8, in order to secure a still tighter grip upon the lead stick.

65 It is evident that as the latter form of

barrel is engaged by the clutch member, and as the said clutch member advances urging the lead stick forward the latter will be exposed to a tight grip preventing it from turning during operation. In case any part of a lead stick should ever clog up the bore 24, the plunger may readily be used to remove such obstacle. It is desired in this connection to emphasize a modification which may very appropriately be made in regard to the end 70 of a pencil opposite the writing point. Thus, as shown especially in Fig. 9, this arrangement contemplates a cap 16 to which is attached the usual rubber eraser 28, an intermediary tubular member 29 being connected 75 in any suitable manner at one end to the barrel 11 and at the opposite end to the said cap member 16, as illustrated in Fig. 9. The member 29 has inside at its middle disposed a disk 30 in order to prevent the lead sticks from falling out, when the cap 16 is removed and invertedly inserted for the purpose of using the rubber eraser. By attaching to the said cap a ring 31, as shown, the pencil may conveniently be connected to 80 a watch chain, thereby securing an easy disengagement between the pencil and the cap and preventing at all times the loss of the said cap with the attached rubber eraser.

It will be evident from the construction, as herein described, that the pencil point may be withdrawn, when not in use, merely by turning the top member in reverse direction.

It is obvious that changes may be made in the form, construction and arrangement 100 of the several parts, as shown, within the scope of the appended claims, without departing from the spirit of the invention, and I do not therefore limit myself to the construction and arrangement shown and described herein.

What I claim as new, and desire to secure by Letters Patent of the United States, is:

1. In a device of the class described, a pencil, comprising a lower barrel having a tube 110 centrally mounted therein, a clutch member engaging the said tube and cooperating with a detachable top-section, the latter being provided with a reduced portion at its lower end and formed with a conical top portion, a bore disposed in the said top section and abrasive means arranged in the latter for the purpose of sharpening the lead.

2. In a device of the class described, a pencil, comprising a lower barrel having a centrally disposed tube member connected thereto at one end, a cylindrically formed space being arranged between the upper portions of the said barrel and tube, a top section having a reduced lower tubular portion threaded upon its inner side and adapted for insertion into said barrel member, a clutch provided with a plunger-arm and having threads disposed upon its outer surface for engagement and cooperation with the said 120

tubular portion of the top section, the said plunger-arm being formed to project into the centrally arranged tube member by means of a slit formed at the side of the latter and 5 extending approximately to the upper edge thereof, and means disposed in the top section for sharpening the lead.

3. In a device of the class described, a pencil, comprising a lower barrel having a centrally disposed tube member connected thereto at one end and forming a cylindrical space between the upper portions of the said barrel and tube, a top section having a reduced lower tubular portion, and shoulders normally resting upon the upper edge of the said barrel, the said tubular portion being threaded upon its inner side and adapted for insertion into the said barrel, a clutch provided with an arm formed with an angular bent at 15 a right angle to constitute a plunger for urging the lead, threads upon the outer surface of the clutch to register with those of the tubular portion, the arm of the said plunger being adapted to project into the centrally arranged tube member by means of a slot formed at the side of the latter and extending almost to the upper edge thereof, and screw-threads disposed in the top section in a manner suitable for the sharpening of the lead.

20 4. In a device of the class described, a pencil, comprising an outer cylindrical and an inner hexagonal barrel, connected at their lower ends only, a longitudinal slit formed at the side of the said inner barrel and extending almost to its upper edge, a conical top section having disposed a central conical bore and being provided with a reduced cylindrical bottom portion suitable for rotation in the space between the outer and inner barrel, 25 the said bottom portion being adapted to cooperate with a clutch member slidably mounted upon the inner barrel, a plunger-arm integral with the said clutch member and made to project into the inner barrel by way of the said slit, for the purpose of engaging a lead-stick, and abrasive means disposed in the conical bore of the top section for sharpening the lead, when the latter by a turning movement of the former is brought into contact 30 with the said sharpening means.

5. In a device of the class described, a pencil, comprising an outer cylindrical barrel having disposed at its center a polygonal barrel, the said barrels having their lower 35 portions rigidly connected, a cap fitted to the said barrels at one end, a top section closing the opposite end, the said top section having its upper portion conically shaped and terminating in a detachable point-segment, the lower part of the said top section being formed intermediately with a shoulder and below the latter with a reduced cylindrical tubular section adapted for insertion between and rotatable engagement with the said two 45 barrel-members, the inner one of these abut-

ting against the point section, when the device is in position for operation, a clutch member having threaded engagement with the tubular member and being of a shape for slidably engaging the said polygonal barrel, the said clutch being provided with an angular plunger for the purpose of urging the lead into contact with the point section, and means disposed in the latter for sharpening the lead.

6. In a device of the class described, a pencil, comprising an outer cylindrical barrel having centrally arranged an approximately, cylindrical inner tube with its outer wall slightly flaring in an upward direction, a longitudinal slit formed in said tube and extending almost to the top thereof, a clutch member adapted to engage said inner tube and slide between the latter and the outer barrel, a plunger having arms formed at a right angle integral with the clutch, and made to engage the lead stick, an upper body having a reduced cylindrical lower portion adapted for insertion between the said lower barrel and inner tube and made to engage the clutch member by means of correspondingly threaded sections, the said upper body member having a point section provided with an inner conical bore; and means disposed in the latter for sharpening a lead stick, substantially as shown and described.

7. In a device of the class described, a pencil, comprising an outer cylindrical lower barrel and an inner approximately cylindrical tube connected at their bottom, the latter tube being formed with a slightly tapered outer wall and an inner wall of even diameter with longitudinal grooves arranged therein, a slit formed in the said tube and extending lengthwise almost to the top thereof, a clutch member adapted to engage said inner tube and slide between the latter and the outer barrel, a plunger having arms formed at a right angle integral with the clutch, and made to engage the lead stick, an upper body having a reduced cylindrical lower portion adapted for insertion between the said lower barrel and inner tube and made to engage the clutch member by means of correspondingly threaded sections, the said upper body member having a point section provided with an inner conical bore; and means disposed in the latter for sharpening a lead stick, substantially as shown and described.

Signed at New York city, in the county of New York, and State of New York, this 5th day of February, A. D. 1929.
